Primary Examiner — Raphael Barkai(74) *Attorney, Agent, or Firm* — Dinsmore & Shohl LLP**CLAIM**

The ornamental designs for a four screen television, as shown and described.

DESCRIPTION

The present specification cross-references U.S. Design patent application Ser. No. 29/499,280, filed on Aug. 13, 2014 and entitled "Single Screen Television With Transparent Sides and Back."

FIG. 1 is a first view showing a top side view.

FIG. 2 is a front view.

FIG. 3 is an isometric view displaying two sides.

FIG. 4 is a left side view.

FIG. 5 is a rear view; and,

FIG. 6 is a right side view.

The device is not limited to the scale shown herein.
